UNITED STATES PATENT OFFICE.

ABRAHAM D. CAMPBELL, OF HACKENSACK, NEW JERSEY, ASSIGNOR OF
ONE-HALF TO WILLIAM CRONKRIGHT, OF SAME PLACE.

TOY OR PUZZLE.

SPECIFICATION forming part of Letters Patent No. 257,655, dated May 9, 1882.

Application filed March 20, 1882. (No model.)

To all whom it may concern:

Be it known that I, ABRAHAM D. CAMPBELL, a citizen of the United States, residing at Hackensack, in the county of Bergen and State of New Jersey, have made an invention of an Improved Toy or Puzzle; and I do hereby declare that the following, taken in connection with the accompanying drawings, is a full, clear, and exact description and specification of the same.

My invention relates to an improved toy or puzzle, the nature of which will be hereinafter fully explained.

According to my invention I arrange a frame or gallows provided at its upper and lower sides with a pair of holes for the reception and passage of a cord or rope, which is so arranged that when in its normal position the said cord or rope shall form two vertical lines, each of which is looped, leaving a central pendent loop. The said cord or rope is knotted at each end or provided with means for preventing it being drawn out from the holes in the lower side of the frame or gallows.

In first arranging the puzzle one end of the cord or rope is passed through one of the holes in the lower frame. It is then conducted upward through one of the holes in the upper frame, brought through on the opposite side, and then looped. It is then passed through the second hole in the upper frame and again looped, and again passed through the second upper hole, after which it is passed downward through the head and trunk of the image or device and secured to the second hole in the lower part of the frame. The parts being thus arranged, the object of the puzzle is to transpose the head of the figure from the second vertical rope or cord to the center, or to the first vertical rope without removal of any part of the device, the transportation being effected by means of changes in the looping of the cord or rope, as will be hereinafter more fully explained.

The accompanying drawings illustrate my invention and form part of this specification.

Figure 1 is a front view of my improved puzzle, showing the parts in their normal positions. Figs. 2, 3, 4, 5, and 6 show the various

positions the parts of the device will assume 50 while the puzzle is being solved.

Similar letters of reference indicate like parts wherever they occur in each of the views.

A represents the frame or gallows; $a a' a'' a'''$, 55 the holes therein.

B is the body or trunk of the figure, and C 55 the head thereof.

D is the rope, the various loops whereof I will designate by different letters of reference in illustrating the solution of my improved 60 puzzle.

The parts being in the position shown by Fig. 1, with the trunk B and head C on the second, D^2 , of the vertical lines of the cord D, in order to operate the puzzle, the first thing 65 to do is to extend the loop d and then pass the head C through the said loop, when the head will assume the position shown by Fig. 2. It will then be simply necessary to take hold of the cord D at d' and d'' and pull upon it until 70 the edge of the loop d is drawn just below the edge of the top A' of the frame A, keeping the head within or above loop d . Then continue pulling the parts d' and d'' , Fig. 3, of the cord until the bottom of the loop passes through 75 the hole a^3 in the top A' of the frame A, when there will be formed on the face of the frame, at the hole a^3 , a double loop, $d^3 d^4$, as represented by Fig. 4. Then pass the head through the double loops $d^3 d^4$ thus formed, after doing 80 which pull back through the hole a^3 the double loop $d^3 d^4$, which will bring the original loop d and the head C into position, as shown by Fig. 5, on the face of the frame A. Then pass the head through loop d and tighten up 85 the said loop d , when the parts will assume the position indicated by Fig. 6. The head will then be in the same relation to the second loop, d^* , in the hole a^2 that it was in relation to loop d in the hole a^3 in Fig. 1, and if it is desired to 90 transport the head C onto the part D' of the cord D, it will only be necessary to repeat the operation hereinbefore described, commencing as if the head C were in the position upon the body B on the part D^2 of the cord D, as shown 95 in Fig. 1. In order to return the head into the original position it is simply necessary to reverse the order of operation.

Having thus described my invention, what I claim is—

1. As a new article of manufacture, a puzzle or toy consisting of a frame or gallows, A, and a suspended body, B, the head C and trunk of which are formed in separate parts and suspended on a looped cord or line arranged and supported substantially as shown and described.
2. As a new article of manufacture, a puzzle or toy consisting of a frame or gallows, A, and a suspended body, B, the head C and

trunk of which are formed in separate parts and suspended on a looped cord or line, so arranged that the head may be removed from one section of the line and placed upon another without removing the head from the line, substantially as set forth. 15

In witness whereof I have hereto set my hand this 18th day of March, 1882.

ABRAHAM D. CAMPBELL.
